S. A. SULECIO

COLLAR BUTTON AND NECKTIE HOLDER

Original Filed June 8, 1921

FIG. 1.

FIG. 2.

FIG. 3.

FIG. 11.

UNITED STATES PATENT OFFICE.

SALVADOR AGUILAR SULECIO, OF SAN FRANCISCO, CALIFORNIA.

COLLAR BUTTON AND NECKTIE HOLDER.

Application filed June 8, 1921, Serial No. 475,917. Renewed October 22, 1923.

To all whom it may concern:

Be it known that I, SALVADOR AGUILAR SULECIO, a citizen of Guatemala, residing at San Francisco, in the county of San Francisco, State of California, have invented a new and useful Collar Button and Necktie Holder, of which the following is a specification, in such full and clear terms as will enable those skilled in the art to construct and use the same.

This invention relates to a collar button and necktie holder and its object is to produce a device upon which a necktie may be formed into a knot and which will permit the tie to remain tied and be placed in position for use and removed therefrom at will without having to repeatedly form the knot thereby extending the wear on the tie.

Another object of the invention is to produce a frame for forming the tie which will be sufficiently rigid to permit the knot to be nicely and tightly tied thereon without bending the frame out of the shape it should occupy to hold the knot in the proper form.

Another object of the invention is to provide the holder with means for connecting it to the collar in such a manner as to prevent it from dropping the necktie and which means is capable of being used either with the form of collar button especially adapted to it or with the ordinary form of collar button having a round head with a round shank such as collar buttons that are in common use.

Another object of the invention is to produce a device for holding the collar end tabs together in such a manner as to more effectively secure the necktie holder in place and to hold the ends of the collar more neatly together than would be the case where the necktie and this holder is applied to the collar without some means of holding the collar ends under the tie.

Another object of the invention is to provide a different shaped holder which can be used with very small neckties when necessary and which holder is substantially the same in construction as the larger holder.

An object of the tie holder is to enable the tie to be used without being tied and untied every time it is to be put on or taken off.

Another object of the invention is to provide a small sized tie holder which can be used in conjunction with small bow ties in a similar way to the larger holder.

Another object of the invention is to produce a collar which will have forwardly projecting wings which will give it an entirely different appearance not obtained in the ordinary forms of collars.

Another object is to produce a collar which will aid in securing the necktie in place thereon.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a perspective view of a collar having a necktie tied on one of the forms illustrated herein secured thereto.

Fig. 2 is a front elevation of the frame. 75

Fig. 3 is an edge view of the frame.

Fig. 4 is a plan view, and

Fig. 5 is an end view of the collar button especially adapted for use with this holder.

Fig. 6 shows the collar button in Figs. 4 and 5 as it appears in use.

Fig. 7 is a modified form of the holder with the holding arms extending straight outwardly instead of being curved around as illustrated in Fig. 2. 85

Fig. 8 is an edge view of the holder shown in Fig. 7.

Fig. 9 is a perspective view of a clamp used for securing the end tabs of the collar together. 90

Figs. 10 and 11 are front elevation and side elevation respectively of a slightly modified form of the invention in which the frame is made very small for the purpose of using a very small tie, and 95

Fig. 12 is a perspective view of the necktie holding frame as it appears when connected with the loop at the front of the collar button shown in Figures 4 and 5.

The collar used is an ordinary form of turned-down collar illustrated at Figure 1 but which in this case has out turned flaps 2 and 3. The necktie holding frame consists of a single piece of wire twisted upon itself as indicated at 4 to produce a transverse bar, the ends of the wire being curved outwardly and upwardly as indicated at 5 and 6 to be inserted between the inner and outer layers of the collar.

The middle of the wire has its sides 7 and 8 extending downwardly from the twisted portion 4 toward each other and at its cen-

ter it is pointed upwardly and backwardly to form the hook shown at 9 as well as to form the open ring like portion 10 shown in Figure 2.

5 The necktie 11 is tied over the frame to form a well designed knot with the hook 9 exposed and when so formed the tie remains in that shape until worn out or discolored.

10 It is in use pushed up with the horns 5 and 6 between the layers of the collar and with the hook 9 either hooked into the outer loop 12 of the collar button 13 or with the ring 10 pushed over the shank of an ordinary collar button. The collar button 13 consists of a single length of wire wound to have an hexangular base portion 15 while from said base portion the remaining part of the wire is extended therefrom and re-

20 versely bent to provide a plurality of short open loops 16. This collar button is then inserted in the collar in the manner illustrated in Figure 6 and it has openings for both of the shirt thicknesses, both of the collar 25 thicknesses and a loop 12 for the hook 9.

If the frame is used without the special button arrangement shown in Figure 4, the frame is pushed up under the collar in precisely the same manner but the loop 10 is 30 pushed over the shank of an ordinary collar button and will firmly hold it in place.

In the form of the invention shown in Figures 7 and 8 the wire is bent in substantially the same way as in the other two figures except that after being twisted around each other the ends 17 and 18 extend outwardly and upwardly from the remaining portion of the frame. The remainder of the frame is precisely the same as the frame 40 shown in the previous form of the invention and consists of two parts 19 and 20 which incline downwardly toward each other and which have the loop 21 for connecting the frame to the ordinary form of collar button, 45 no other form of device being necessary.

This form also has a hook at 22 the same as the hook 9 to enable it to be applied to the form of collar button shown in Figure 4 if that is desired. Sometimes it may happen that the ends of the collar do not stand close enough together, by applying the clamp shown in Figure 9 to the ends of the collar corners the collar ends will be held close together. This clamp consists of a single piece of wire bent into two U-shaped forms 25, 26 and connected together with two transverse bars at the top. This clamp is usable only where the collar ends stand some distance apart.

60 Figures 10 and 11 are smaller to show the type of form similar to that of the other

figures except that it is made upon a much smaller scale and intended to be particularly for the purpose of fastening smaller neckties, which consists of a single piece of wire with the ends wound together at 30 and with four projecting horns 31 to 34 inclusive. It is also provided with a hook and loop 35 which enables it to be fastened to the collar button shown in Figure 4 or to be fastened to the ordinary form of collar button with round head.

The collar button used in conjunction with this necktie holder is made of a single piece of wire and while it has no head at the same time its special crimped form presents five receptacles or places in which shirt band and collar band may be held while at the same time it has a loop for the hook on the necktie holder.

80 It will be understood that most persons wear shirts that open in front so that there are two thicknesses of shirt band as well as two thicknesses of collar band to be provided for while in addition there must be a loop in the collar button for this necktie holder to be hooked into. The absence of an enlarged head is also an advantage in that no strain is put upon the shirt band in inserting the button in the buttonhole and at 90 the same time by reason of the loop shape the size of the shirt band and collar is increased slightly.

85 What I claim is as follows, but various modifications may be made in the construction shown in the drawings and above particularly described form, within the purview of my invention:

1. A wearing apparel apparatus comprising a frame for forming a necktie knot, said frame having a hook at one end and a pair of laterally projecting arms at the other end, and a collar button having an open slot to receive the hook on the frame.

100 2. An apparatus of the class described comprising a triangular shaped frame having a hook at one apex of the triangle and having projecting arms at each other apex, and a button having a slot therein to cooperate with the hook to hold the necktie in 110 place on the collar.

115 3. An apparatus of the class described comprising a necktie frame having a pair of arms to engage a collar at one end, and having a double hook at the other end with a retaining button having a loop to engage one of said hooks and having other open loops to engage and hold the several parts of the shirt and collar.

120 In testimony whereof I have hereunto set my hand this 28 day of May, A. D. 1921.

SALVADOR AGUILAR SULECIO.
